COIN HEAD FOR COIN CONTROLLED DEVICES

Thomas W. B. Watling, Chicago, Ill., assignor to
Watling Scale Company, Chicago, Ill., a corpora-
tion of Illinois

Application September 19, 1935; Serial No. 41,217

4 Claims. (Cl. 194—92)

This invention relates to what is known as a coin head for coin controlled trips for operating weighing scales, vending machines, and the like. Such coin operated machines are commonly located in such public places as railway stations, hotels, lunch rooms, etc., and in many cases it has hitherto been possible for a dishonest employee of the establishment where the machine is located to cheat the owner of the machine by removing a portion of the collected coins therein.

One object of the present invention is to provide a coin head for such machines that will prevent the surreptitious abstraction of part of the deposited coins without giving notice to the proprietor of the machine of the loss of such coins, and the amount abstracted; and this object is accomplished by incorporating in the coin head an improved counter mechanism that registers each coin going through the machine each time the coin depositing member makes a full in-stroke.

The efforts put forth by petty crooks to cheat coin operated machines and devices are, in number, variety and crudity, little short of amazing. Such articles as slugs, buttons, chewing gum, hair pins, and many other curious frauds are attempted to be used in place of the legitimate penny, nickel, dime or other coin called for by the machine. For this reason, the mechanism for passing the coin to the point where it trips into action the pointer of a weighing machine or the delivery device of a vending machine often becomes clogged and disabled, and then the coin head has to be opened up, cleaned of obstructions, repaired if damaged, and restored to working condition. All this takes time and labor, and another object of the invention is to provide a construction of coin head that shall have an easily removable and applicable cover for the relatively movable parts of the mechanism, so that the latter can be readily gotten at for cleaning and repairs.

Still another object is to provide a coin head equipped with a removable cover normally locked thereon by a key, and wherein the coin depositing mechanism of the head will be inoperative unless the cover is in place; and this is accomplished by means of an element carried by the cover which forms part of the lower cover lock and also cooperates with the trailing end of the coin in the coin slide to hold the coin flat in its seat and prevent the blocking of the coin slide by a tilting movement of the coin itself. This cover balks dishonest efforts to operate the

mechanism by a false coin or coin substitute by first removing the cover.

Other objects and attendant advantages of the invention will be apparent to persons familiar with devices of this character from the following description, taken in connection with the accompanying drawing:

Fig. 1 is a top plan view of the device, in horizontal section through the cover on the line 1—1 of Fig. 2, showing the coin slide fully retracted. 10

Fig. 2 is a longitudinal section taken on the line 2—2 of Fig. 1.

Fig. 3 is a fragmentary section, similar to Fig. 2, showing the coin slide advanced without a coin therein and automatically blocked against 15 making a sufficient stroke to actuate the counter.

Fig. 4 is a fragmentary plan view, partly in section, of the parts in the position shown in Fig. 3, taken on the line 4—4 of Fig. 3.

Fig. 5 is a transverse section taken on the line 5—5 of Fig. 2.

Referring to the drawing, 10 designates as an entirety a cast metal frame adapted to be secured to the cabinet of the coin controlled scale, vending machine, or the like, with which the device is associated. Secured as by screws 11 to the flat top of the frame 10 is the base plate 12 formed with upwardly and inwardly turned edge portions that constitute slideways 13 for the flat coin slide 14. Base plate 12 is formed with front and intermediate holes 15 and 16, respectively, both of which are of less diameter than the coin adapted to be used, and, beyond the hole 16 is a rear hole 17 of a diameter larger than the coin and through which the latter is discharged.

The coin slide 14 is formed with a single hole 18 of a size to just be filled by the coin.

Secured to and between the rear portions of the slideways 13 is a flat plate 19 having a longitudinal counter sunk portion 20 in which is formed a longitudinal slot 21. Secured to or integral with the plate 19 on opposite sides of the slot 21 are a pair of lugs 22 in and between which is pivoted at 23 a stop finger 24 normally urged downwardly into the hole 16 by a leaf spring 25.

If the coin slide 14 be actuated without any coin therein, the finger 24 will pass through the coin hole 18 of the slide and also the underlying hole 16, and will thus block further inward movement of the coin slide, as clearly shown in Fig. 3. On the other hand, if there be a proper coin in the seat 18 of the coin slide, the coin, through engagement with the nose of the stop finger 24, will hold the latter out of said holes and thus permit a full 55

in-stroke of the coin slide until the coin seat 18 registers with the rear hole 17 of the base plate, whereupon the advance edge of the coin will engage with a depending coin ejector cam 26 to 5 eject the coin. This coin ejector cam 26 is formed as a cut-out and downwardly bent portion of a bridge plate 27, the forward portion of which bridge plate overlies the rear portion of the plate 19 and is attached thereto by screws 28, 10 and the rear portion of which is attached by a downwardly bent ear 29 and screw 30 to the frame 10.

To permit a full in-stroke of the coin slide beyond the ejection cam 26, the slide is formed with 15 a longitudinal slot 31 that straddles the ejection cam, as clearly shown in Fig. 4.

Referring next to the improved counter mechanism, which forms an important feature of the present invention, 32 designates a counter of any 20 known make, the base of which is mounted by screws 33 on the bridge plate 27. Fast on the shaft of the counter is a depending arm 34 that lies across the path of the inner or forward end of the coin slide, so that when the slide is given 25 a full stroke, its inner end strikes the counter arm 34 and swings the same sufficiently to register one coin on the counter 32. The counter arm, when actuated, is returned to normal position by a pull spring 35, in which position its free end portion 30 is arrested by a stop 36 consisting of an end edge portion of the base plate 12.

The device is also equipped with a known form of full stroke compelling device, consisting of a pivoted dog 37 cooperating with a toothed rack 38 on one edge of the coin slide 14, and a pull spring 39 that causes the dog to lockingly engage 35 with the teeth of the rack alternately from opposite ends of the latter, in a well-known manner, so as to compel full in and out strokes of the coin 40 slide before the latter can be actuated in the opposite direction.

40 designates the cover member, the margins of the sides of which are counter sunk to fit the margins of the base frame 10, as best shown in 45 Figs. 1 and 2. In the upper transverse wall of the cover is mounted a lock 41, on the inner end of the key-actuated shaft of which lock is an arm 42 equipped at its free end with a lateral locking pin 43 adapted to ride beneath a cam surface 44 50 on the rear end edge of the bridge plate 27, so as to thereby lock the upper end of the cover to the frame. Attached to the interior of the cover at the lower end of the latter is a transverse bar 45 55 formed with a downwardly offset flat central portion 45' (Figs. 1 and 2), that, when the cover is applied, slides beneath a projecting tongue 46 formed as an extension of plate 19, whereby the lower end of the cover is also locked in place. The bar offset 45' has another function in connection 60 with the operation of the coin slide. If the bar 45 were not present, when the forward portion of the coin slips beneath the nose of the stop finger 24, the pressure of the finger would tilt the coin so that its forward or advance edge would collide 65 with the forward edge of the hole 16, and thus block further inward movement of the coin slide. This tilting movement however, is prevented by the bar 45, the portion 45' of which, at the time the forward edge of the coin passes beneath the 70 nose of the finger 24, overlies the rear or trailing portion of the coin, so that the latter cannot tilt, and thus passes on until it is discharged through the hole 17 by the cam 26.

Of course, the hole 15 in the base plate might 75 be omitted, and the hole 16 might be substituted

by a slot wide enough to receive the stop finger 24, if the device were always operated with the coin for which it is designed. But, as above pointed out, the hole 18 of the coin slide frequently becomes clogged with non-fitting slugs, 5 buttons, hair pins, wads of chewing gum and all sorts of other fraudulent articles; and at such times the holes 15 and 16 in the base plate facilitate the removal of such articles by an upward pressure of the thumb or finger from beneath 10 without the necessity of disassembling the parts and removing the coin slide.

From the foregoing it will be seen that the described device registers every coin that is passed through it, so that when the coins are collected, 15 if the number received is less than the number shown by the counter, the collector has notice that the machine has been tampered with and robbed.

Of course, modifications of the structural details may be made within the scope of the claims. 20

I claim:

1. In a coin head of the type described, the combination with a frame, of fixed locking members mounted on said frame at opposite ends thereof respectively, mechanism, including a slidable coin holder for conveying a coin through, and discharging it from, said head, mounted on said frame, and a removable cover for said mechanism having at its opposite ends locking members respectively cooperating with the locking members on said frame to lock said cover to said frame, one of the locking members on said cover cooperating with said mechanism through engagement with a coin in said holder to render said mechanism operative. 35

2. In a coin head of the type described, the combination with a frame, of a base plate mounted on said frame formed with a coin discharge opening at its inner end and with channel guides on its longitudinal edges, a coin holder slide on said base 40 plate engaged with said channel guides and having a coin receiving hole, a bridge plate spanning said channel guides and said slide and having an integral depending portion extending vertically through said discharge opening and formed with 45 an inclined cam edge adapted to deflect a coin downwardly through said opening, a counter mounted on said bridge plate, and an actuating arm on the shaft of said counter the free end of which lies across the path of said slide and is actuated by the inner end of said slide on a full 50 stroke of the latter.

3. In a coin head of the type described, the combination with a frame having a base plate 55 formed with an opening, of a slide on said base plate having a coin receiving hole adapted to overrun said opening when said slide is moved inwardly, a pivoted spring pressed locking finger overhanging said opening with its free end riding 60 on said slide, said finger being projected through both said hole and said opening when the empty slide is pushed inwardly, a removable cover for said base plate and slide, and a member carried by said cover adapted, through contact with the 65 trailing portion of a coin in said slide to prevent tilting of the coin under the pressure of said finger on its forward portion as the coin travels across said opening.

4. In a coin head of the type described, the combination with a frame having a base plate formed with an opening, of a slide on said base plate having a coin receiving hole adapted to overrun 70 said opening when said slide is moved inwardly, a pivoted spring pressed locking finger overhang- 75

ing said opening with its free end riding on said slide, said finger being projected through both said hole and said opening when the empty slide is pushed inwardly, a removable cover for said base plate and slide, and interengaging locking members on said base plate and cover, the locking member on said cover consisting of a bar attached

to the inner side of the cover adapted through contact with the trailing portion of a coin in said slide to prevent tilting of the coin under the pressure of said finger on its forward portion as the coin travels across said opening.
